UNITED STATES PATENT OFFICE

INGEMAR K. RYSTEDT, OF DAYTON, OHIO, ASSIGNOR TO THE RYSTEDT ENGINEERING COMPANY, OF DAYTON, OHIO, A CORPORATION OF OHIO

COUPLING DEVICE

Application filed May 21, 1923. Serial No. 640,449.

This invention relates to a coupling device and is designed more particularly as a terminal clamp for connecting a conductor with a storage battery.

5 One object of the invention is to provide a device of this kind by means of which a conductor may be quickly and easily connected with or disconnected from the terminal.

10 A further object of the invention is to provide such a device which will constitute a very strong rigid mechanical connection between the conductor and the terminal and will establish perfect electrical connection between 15 these parts.

A further object of the invention is to provide a device of this kind which is simple in its construction and operation and which may be produced at a low cost.

20 Other objects of the invention will appear as the device is described in detail.

In the accompanying drawings Fig. 1 is a plan view of the coupling device of my invention showing the same applied to the terminal stud of a storage battery; Fig. 2 is a side elevation of the same; Fig. 3 is a longitudinal sectional view taken centrally through the coupling device; Fig. 4 is a side elevation of the coupling member; Fig. 5 is a plan view 30 of the coupling member; and Fig. 6 is a front elevation of the clamping member.

In these drawings I have illustrated one embodiment of my invention and have shown the same as comprising a coupling member 35 having a part 1, which is preferably annular in form, to embrace the terminal stud 2 of the storage battery. The opening in the annular coupling member is of such a diameter that it will readily slip onto and off of the terminal. A conductor 3 may be connected with the coupling member in any suitable manner but, in the present device, the annular portion of the coupling member is provided with a radial projection, preferably in the form 45 of a hollow stud 4, adapted to receive the end of the conductor. As here shown the bore of the hollow stud is of such a size that it will receive the conductor only, the insulation 5 of the cable abutting against the end of the 50 boss. The cable may be secured within the

hollow boss by sweating the same therein by means of solder introduced through the inner end of the bore of the boss.

Slidably mounted upon the projection or hollow boss 4 is a clamping member 6 having parts arranged on opposite sides of the coupling member to engage the terminal 2. As here shown this clamping member is U-shaped in cross section and its intermediate portion is provided with an opening 7 to receive the hollow boss and its end portions are bent into substantially parallel positions to form contact plates 8 and 9. The inner edges of the plates 8 and 9 are adapted to engage the adjacent surface of the terminal and they are of such width that they may extend for a considerable distance beyond the inner edge of the annular coupling member, thereby enabling the device to be applied to a stud of a diameter considerably less than the diameter of the coupling member. The edges of the contact plate which engage the terminal may be of any suitable character but I prefer to provide them with cutting edges so that they will penetrate any accumulation of dirt or any glazed surface on the terminal and thus establish perfect electrical contact therewith. As shown at 10 in Figs. 1 and 6, the contact plates are provided with curved seats to conform substantially with the curvature of terminal and these seats are serrated.

The clamping member may be moved into and out of engagement with the terminal in any suitable manner but I prefer to employ a nut 11 which is screw threaded onto the hollow boss 4 and can be readily manipulated to force the clamping plates against the terminal with any desired amount of pressure and which will firmly hold the clamping member in its adjusted position.

It will be apparent that I have produced a terminal clamp which is very simple in its construction and very easily operated. To apply the same it is only necessary to retract the nut 11 far enough to permit the withdrawal of the clamping plates out of alignment with the opening in the coupling member. The coupling member is then placed about the terminal and the nut actuated to force the clamping plates into firm contact

therewith. The contact plates engaging the terminal on both sides of the coupling member establish a very firm rigid connection between the parts, and the cutting edges of the plates penetrating the surface of the terminal, which is usually of lead, establish good electrical contact therewith.

While I have shown and described one embodiment of my invention I wish it to be understood that I do not desire to be limited to the details thereof as various modifications may occur to one skilled in the art.

Having now fully described my invention what I claim as new and desire to secure by Letters Patent, is:

In a coupling device of the character described, a coupling member having an annular portion to embrace a terminal stud and having a laterally extending boss adapted to receive one end of a conductor and provided with external screw threads, a substantially U-shaped clamping member having an apertured transverse portion extending about and slidably supported on said boss and having substantially parallel portions arranged on opposite sides of said coupling member and provided with edges to engage said stud on the respective sides of said coupling member, and a nut screw threaded onto said boss to engage said clamping member and force said edges into contact with said stud and to draw said coupling member into firm contact with said stud, thereby causing said coupling device as a whole to be rigidly secured to and supported by said stud.

In testimony whereof, I affix my signature hereto.

INGEMAR K. RYSTEDT.
